DESIGN FOR A LIGHTING UNIT

Jacob H. Blitzer, New York, N. Y., assignor to
Lightolier Company, New York, N. Y., a corpo-
ration of New York

Application November 10, 1934, Serial No. 53,961

Term of patent 7 years

To all whom it may concern:

Be it known that I, Jacob H. Blitzer, a citizen
of the United States, and residing at New York,
in the county of New York and State of New
York, have invented a new, original, and orna-
mental Design for a Lighting Unit, of which the
following is a specification, reference being had
to the accompanying drawing, forming part
hereof, and in which

Fig. 1 is a side elevation of the unit showing
my new design, and

Fig. 2 is a fragmentary bottom view there-
of.

The dominant feature of the design resides in
the portions shown in full lines.

I claim:—

The ornamental design for a lighting unit, sub-
stantially as shown and described.

JACOB H. BLITZER.
